(57) **CLAIM**

The ornamental design for a pill container, as shown and described.

DESCRIPTION

FIG. 1 is a perspective view from above of the pill container of my new design with the lid, individual segments, and the base separated for purposes of illustration.

FIG. 2 is a perspective view from below thereof, with the base, individual segments, and the lid being separated for purposes of illustration.

FIG. 3 is an elevational view from the front thereof. The elevational view of the rear is a mirror image thereof.

FIG. 4 is an elevational view of the left side thereof, as shown in FIG. 1.

FIG. 5 is an elevational view of the right side thereof, as shown in FIG. 1.

FIG. 6 is a top plan view thereof, showing the separated lid, three individual segments, and the base, respectively.

FIG. 7 is a bottom plan view thereof, showing the separated base, three individual segments, and the lid, respectively; and, FIG. 8 is a perspective view of the pill container of my new design with all segments being vertically aligned.

The broken line figure in FIG. 1, showing a hand, is for purposes of illustration, and the hand is not a part of my new design.

The additional broken line environment disclosed in FIG. 1 forms no part of the claimed design.
